(74) *Attorney, Agent, or Firm* — KLEMCHUK PLLC

(57) **CLAIM**

The ornamental design for a plunger pot spindle, as shown and described.

DESCRIPTION

FIG. 1 is a perspective view of a plunger pot spindle showing my new design;

FIG. 2 is a right side view thereof;

FIG. 3 is a left side view thereof;

FIG. 4 is a top view thereof;

FIG. 5 is a bottom view thereof;

FIG. 6 is a front view thereof; and,

FIG. 7 is a rear view thereof.

The broken lines shown in the Figures represent environmental subject matter or portions of the plunger pot spindle that form no part of the claimed design.

1 Claim, 7 Drawing Sheets
